United States Patent Office

Des. 196,836
Patented Nov. 12, 1963

196,836

GARDEN UTILITY CART

Bernard B. Berger, Aiken, S.C., assignor to National Steel Cabinet Company, Edgefield, S.C., a corporation of Illinois

Filed July 26, 1962, Ser. No. 71,059

Term of patent 3½ years

(Cl. D14—3)

FIG. 1 is a perspective view of a garden utility cart embodying my new design.

FIG. 2 is a rear elevational view thereof.

I claim:

The ornamental design for a garden utility cart, substantially as shown.
